UNITED STATES PATENT OFFICE.

WILLIAM P. MURPHY, OF SAN JOSÉ, CALIFORNIA, ASSIGNOR OF ONE-HALF
TO A. E. WINLOW, OF WILLOWGLEN, CALIFORNIA.

DESIGN FOR AN EGG-HOLDER.

SPECIFICATION forming part of Design No. 30,526, dated April 11, 1899.

Application filed March 14, 1899. Serial No. 709,093. Term of patent 7 years.

To all whom it may concern:

Be it known that I, WILLIAM P. MURPHY, a citizen of the United States, residing at San José, in the county of Santa Clara and State of California, have invented and produced a certain new and original Design for Egg-Holders; and I do declare the following to be a full, clear, and exact description of the invention, such as will enable others skilled in the art to which it appertains to make and use the same.

The invention has relation to a new and original design for an egg-holder; and it consists of a design of the configuration shown in the accompanying drawing, in which I have illustrated the invention in perspective.

The leading features of the design consist in a ring *a*, having radiating rods *b*, from the

center or intersection of which projects vertically the rod *c*, having a handle *d* at its upper end.

²⁰
f denotes short wires arranged equidistant apart and projecting downwardly from the periphery of the ring.

What I claim is—

The design for an egg-holder as herein shown and described.

In testimony whereof I have hereunto set my hand in presence of two subscribing witnesses.

WILLIAM P. MURPHY.
